UNITED STATES PATENT OFFICE.

EDMUND L. BROWN, OF MARTINSVILLE, INDIANA.

DESIGN FOR A ROCKING-CHAIR.

SPECIFICATION forming part of Design No. 36,224, dated February 10, 1903.

Application filed December 16, 1902. Serial No. 135,463. Term of patent 7 years.

To all whom it may concern:

Be it known that I, EDMUND L. BROWN, a citizen of the United States, residing at Martinsville, in the county of Morgan and State of Indiana, have invented and produced a certain new, original, and ornamental Design for Rocking-Chairs, of which the following is a specification, reference being had to the accompanying drawing, forming part thereof.

As shown in the drawing, the rocking-chair has four posts, all of which are curved inwardly at their middle portions. All of the posts extend above the seat of the rocking-chair, and the two front posts A A are connected by curved arms B B with the back posts C C of the rocking-chair. The arms have the expanded flat upper surfaces b b, with underlying downwardly-tapering solid portions forming arms, which are wedge-shaped in vertical section and which are separated by open spaces from the chair-seat D and by open spaces from the front posts A. The inside surfaces of the arms merge into the front surface of the back E of the rocking-chair without any break in the surface.

The rear posts C C are continued above the arms, as shown, and are connected near their tops by the curved bar F. The back E is continued without any break in its surface from the curve connecting the bottoms of the 30 arms to the bar F. The back arms and seat are covered with splints woven together in the design shown in the drawing. The posts and cross-bars forming the frame of the chair are covered with the natural bark of the wood 35 from which they are made. The rockers are indicated by the dotted lines of the drawing.

Having described my invention, what I claim as new, and desire to secure by Letters Patent, is—

The ornamental design for a rocking-chair, as herein shown and described.

In witness whereof I have hereunto set my hand and seal, at Martinsville, Indiana, this 4th day of December, A. D. 1902.
